UNITED STATES PATENT OFFICE.

JOHN WALDHEIM, OF ELIZABETH, NEW JERSEY, ASSIGNOR TO UNDERWOOD TYPE-WRITING COMPANY, OF NEW YORK, N. Y., A CORPORATION OF DELAWARE.

TYPEWRITING MACHINE.

Application filed December 17, 1919. Serial No. 345,515.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

This invention relates to typewriting machines, and more particularly to mechanism for varying the position of the platen with respect to the printing point, so as to cause more uniform wear of the platen and thereby increase the life of the platen.

15 An object of the present invention is to provide means whereby each release or cast-off of the feed-rolls from the platen will effect the shifting of the latter with reference to the printing point.

20 Another object of the invention is to provide improved means whereby a fractional line-space movement of the platen with reference to the line-space wheel may readily be effected.

25 According to the present invention, the platen is connected with its driving shaft by means of differential gearing controlled by a sleeve on the shaft. Normally, the differential gearing and the sleeve rotate with 30 said shaft, and the platen is rotated as if fixed on the platen shaft. When, however, the feed-rolls are released or cast-off for insertion of work-sheets, or any other purpose, the sleeve will be rotated on the shaft 35 and a reduced movement given to the platen.

Provision may also be made whereby the platen will be shifted longitudinally by the feed-roll-release mechanism.

40 Fractional line-space adjustment of the platen may be effected by means of a finger-wheel fixed on the sleeve, which controls the differential gearing.

Inasmuch as the feed-roll-release mechanism is usually actuated to enable insertion 45 of work-sheets, shifting of the platen, with sufficient frequency, is insured, and, at the same time, there will be no shifting during the typing of a single sheet, which would alter either the line-space positions, or the 50 letter-space positions of the platen relative to the printing point.

Other features and advantages will hereinafter appear.

In the accompanying drawings,

Figure 1 is an end elevation of a platen 55 frame, showing the connection between the feed-roll-release device and the ratchet wheel by means of which the differential gearing may be actuated.

Figure 3 is a longitudinal sectional view 60 taken along the line 2—2 of Figure 3, showing the arrangement of the teeth on the internal gears.

Figure 3 is a longitudinal sectional view 65 of the platen and associated parts.

The platen comprises a cylindrical sheath 1 of suitable material, such as rubber, mounted on a hollow core 2, preferably of wood, and heads 3 and 4 secured to the core 2 by means of screws 5, the left-hand head 3 being journaled on a shaft 6, and the right-hand head 4 being journaled on a sleeve 7, rotatably mounted on shaft 6. It will be seen that the left-hand head 3 is provided with a circular flange 3^a, which fits 75 the bore of the hollow core 2.

In order to support the platen in the usual platen frame 8, the shaft 6 is journaled in the left-hand end of the platen frame and in the sleeve 7, which, in turn, is journaled in the right-hand end of the platen frame. Shaft 6 may be turned by means of 80 a line-space or ratchet wheel 9, fixed on the shaft 6 at the left of the platen, or by means of finger-wheels 10.

The ratchet wheel 9 may be yieldably maintained in position by means of a detent roll 11 on a pivotally mounted arm 12 urged toward the ratchet or line-space wheel 9 by 85 a spring 13.

The means for actuating the ratchet wheel or line-space wheel 9 may be like that used in the Underwood machine and, in general, is the same as that shown in the patent to Alfred G. F. Kurowski, No. 1,190,658, 90 granted July 11, 1916, and the actuating means may be set for one, two or three line-space movements by means of a regulator lever 14.

For the purpose of driving the platen 100 from the shaft 6, an internal gear 15 is placed in a recess 15^a in the right-hand end of core 2. A hub 16, extending to the left (Figure 3) from said gear, projects into the core 2, which is provided with a bearing 105 member 17 to prevent undue wear of said

- core. The internal gear 15 is provided also with a hub 18 extending in the opposite direction to give a better bearing for the gear 15 on shaft 6. A spline or key 19 on shaft 5 6 engages in a slot or groove 20 in hub portions 16 and 18, thus providing means whereby the internal gear 15 will be rotated with shaft 6 and may be shifted longitudinally thereof.
- 10 The head 4 of the platen is provided with an internal gear 21 of the same diameter as gear 15, but having a slightly larger number of teeth. It will be seen that the internal gear 21 will serve to maintain the internal gear 15 in the recess 15^a of the core 2. A driving connection between gears 15 and 21 may be effected by means of a pinion 22 constantly in mesh with both of said gears. This pinion is supported on a stud 20 23 in an arm 24 carried by sleeve 7.
- 25 In line-spacing by means of the line-space wheel 9, sleeve 7 will turn with shaft 6 and pinion 22 will act merely as a connector between the two internal gears 15 and 21, which will rotate together, thereby effecting rotation of the platen in accordance with the movement of the line-space wheel.
- 30 The arrangement of the different parts is such that the frictional resistance to the turning of sleeve 7 is insufficient to prevent movement thereof with the driving shaft. If, however, the sleeve 7 is rotated with reference to shaft 6, pinion 22 will be rotated by gear 15, which normally will be held against movement due to the engagement of detent roll 11 with the line space wheel, and, due to the difference in the number of teeth between the internal gears, will shift gear 21 with reference to gear 15 a distance proportional to the number of teeth passed over. As seen in Figure 2, the pitch or distance between the teeth of gear 21 is less than on gear 15. Therefore, when pinion 22 is moved to the right over one tooth 40 45 of gear 15, the next notch of gear 21 will be brought into alignment with the next notch of gear 15, thus causing the former to be advanced a distance equal to the difference in pitch between the two intervals. Obviously, if pinion 22 is advanced further, the advanced movement of gear 21 will be proportional to the number of teeth of gear 15 passed over by pinion 22. Movement of pinion 22 in the reverse direction will effect 50 55 a reverse movement of gear 21.
- 60 The sleeve 7 may be held against longitudinal movement by means of a spacing sleeve 25, engaging the right-hand side of the platen frame 8, and by a finger-piece 26, having a hub 27 in contact with spacing sleeve 25 and secured to the sleeve 7 by means of a set screw 28. Sleeve 7 is held against outward movement by means of a hub 29 of a fine-toothed ratchet wheel 30, 65 secured to sleeve 7 by means of a set screw
31. Obviously, actuation of ratchet wheel 30 will effect a rotary shifting of the platen with reference to shaft 6.
- Provision is also made for shifting the platen longitudinally with reference to the shaft 6. To this end, the fine-toothed ratchet wheel 30 is provided with a cam 32 for engaging a projection 33 on the right-hand head 4 of the platen, the platen being yieldably urged toward the cam by means of a helical spring 34, supported on a hub 35 projecting to the left from the left-hand platen head 3, and engaging at opposite ends the left-hand head 3 of the platen and the left-hand end of the platen frame 8.
- It will be seen that the internal gear 15 will move with the platen and that the length of hub 18 must be limited so as to allow the platen to move to the right as far as desired. Also, since sleeve 7 is held against longitudinal movement, pinion 22 must be of sufficient length to maintain engagement with the internal gears 15 and 21 during the shifting of the latter.
- According to the present invention, ratchet wheel 30 is actuated by the release mechanism for the usual front and rear feed-rolls 36 and 37, respectively. Said feed-rolls 36 and 37 are carried on levers 38 and 39, respectively, having depending arms 40 and 41, respectively, in engagement with cam portions of the release shaft 42 supported in brackets 43. Said feed-rolls are normally maintained in engagement with the platen by springs 37.
- The usual feed-roll-release finger-piece 44 is pivoted at 45 on the platen frame and connected by means of a link 46 with an arm 47 fixed on shaft 42. In order to actuate the ratchet wheel 30 from the feed-roll-release mechanism, a pawl 48 is pivoted at 49 on an ear projecting from link 46, and, when the link is in its downward position, said pawl is maintained in ineffective position by means of a tail 50, forming part thereof, engaging the right-hand bracket 43. Upon actuation of the finger-piece 44, the pawl 48 will be lifted, and, when permitted by tail 50 and bracket 43, will be moved by spring 51 on link 46 into engagement with said ratchet wheel 30.
- It will be evident that each time the feed-roll-release mechanism is moved to the dotted-line position, shown in Figure 1, the ratchet wheel 30 will be advanced and the platen shifted a fractional part of a line-space, and also longitudinally either against the opposition of spring 34, by the cam 32 or in the opposite direction, when permitted by said cam.
- It will be evident also that the platen may be adjusted a fractional part of a line-space by means of said finger-piece 26 to position a work-sheet relatively to the printing point when the feed-rolls are effective.

Variations may be resorted to within the scope of the invention, and portions of the improvements may be used without others.

Having thus described my invention, I claim:

1. In a typewriting machine, in combination, types, a revolute platen, feed-rolls to co-operate therewith, feed-roll cast-off mechanism, and means actuated by said cast-off mechanism for effecting a slight surface displacement of the platen to vary the portions of the platen exposed to the impact of the types.

2. In a typewriting machine, in combination, a revolute platen, feed-rolls to co-operate therewith, feed-roll cast-off mechanism, and means actuated by said cast-off mechanism for effecting a shift of said platen in a direction longitudinally thereof, to vary the position of the same relatively to the printing point.

3. In a typewriting machine, in combination, a revolute platen, feed-rolls to co-operate therewith, feed-roll cast-off mechanism, and means actuated by said cast-off mechanism for effecting a fractional line-space movement of said platen, to vary the position thereof relatively to the printing point.

4. In a typewriting machine, in combination, a revolute platen, feed-rolls yieldably urged thereagainst, a line-space wheel, means for normally actuating said platen in accordance with the actuation of said line-space wheel, feed-roll cast-off mechanism, and means actuated by said cast-off mechanism for shifting said platen relatively to said line-space wheel.

5. In a typewriting machine, in combination, a platen, comprising heads, a platen frame, a sleeve mounted in one end of said platen frame, a shaft extending through said sleeve and journaled in the other end of said platen frame, one head of said platen being rotatably mounted on said sleeve, and the other head being rotatably mounted on said shaft, an internal gear splined on said shaft and positioned in a recess in the adjacent end of said platen, an internal gear of a different number of teeth adjacent said first-mentioned internal gear and fixed to said platen, said platen and internal gears being movable together longitudinally of said shaft, and a pinion, on an arm carried by said sleeve, meshing with said internal gears and being of sufficient length so as to remain in mesh therewith when the platen is shifted longitudinally.

6. In a typewriting machine, in combination, a platen, means, including a shaft coaxial therewith, to actuate the same, means, including a ratchet wheel, to shift said platen relatively to said shaft, feed-rolls yieldably pressed against said platen, means for casting off said feed-rolls, including a cast-off shaft, a bracket near one end of the

platen for supporting said cast-off shaft, an arm at the end of said shaft, a pivoted finger-piece, a link connecting said finger-piece with said arm, and a spring-pressed pawl pivotally mounted on said link and having a tail connected therewith, said tail engaging said bracket when the link is in depressed position and maintaining the pawl in retracted position, said spring-pressed pawl being moved into engagement with said ratchet wheel when said link is lifted.

7. In a typewriting machine, in combination, a platen, a platen shaft, differential gearing connecting said shaft and said platen, said differential gearing being normally ineffective to change the relation between said platen and said shaft, feed-rolls co-operating with said platen, feed-roll cast-off mechanism, and means actuated by said cast-off mechanism to operate said differential gearing, and thereby cause a relative movement between said platen and said shaft.

8. In a typewriting machine, in combination, a platen, a platen shaft along which said platen is shiftable, a platen frame in which said platen shaft is supported, means urging said platen in one direction along said shaft, means, including a cam, for acting in opposition to said urging means, to determine the position of said platen, feed-rolls co-operating with said platen, feed-roll cast-off mechanism, and means actuated by said cast-off mechanism for shifting said cam, and thereby changing the position of said platen longitudinally with respect to the platen shaft.

9. In a typewriting machine, in combination, a platen, a line-space wheel, means for feeding said platen in accordance with the actuation of the line-space wheel, feed-rolls co-operating with said platen, feed-roll cast-off mechanism, and means actuated by said cast-off mechanism for shifting said platen relatively to said line-space wheel.

10. In a typewriting machine, in combination, a platen, a platen shaft, differential gearing connecting said platen and said shaft, and a finger-piece rotatable on said shaft for controlling said gearing, said finger-piece being normally held against rotation relatively to said shaft, but effective when turned relatively to said shaft to actuate said differential gearing to effect a reduced movement of said platen relatively to said shaft.

11. In a typewriting machine, in combination, a revolute platen, a platen shaft, an internal gear connected with said shaft to rotate therewith, an internal gear of the same diameter, but having a different number of teeth, connected with said platen to move therewith, a sleeve on said shaft, a finger-wheel on said sleeve, and a pinion eccentrically mounted on said sleeve and meshing

with both of said internal gears, said sleeve normally turning with said shaft, and thereby causing said platen and said shaft to move together.

5 12. In a typewriting machine, in combination, a platen, a driving axle therefor, connecting means whereby the platen is normally rotated in accordance with the rotation of said axle, feed-rolls yieldably urged 10 toward said platen, feed-roll cast-off means, and means actuated by said cast-off means for shifting said connecting means, so as to vary the position of said platen on said axle.

13. In a typewriting machine, in combination, a platen, a driving axle therefor, connecting means normally effective to maintain said platen fixed with respect to said axle, and means to shift said connecting means to vary the position of said platen on said axle, comprising a ratchet-wheel, a pawl for actuating the same, and manually-operable means for reciprocating the pawl.

14. In a typewriting machine, in combination, a platen, a driving axle therefor, two gears of the same diameter, but of different pitch, connected to said platen and driving axle, respectively, to rotate therewith, connecting means including a pinion meshing 30 with both of said gears, normally causing said platen to rotate with said axle, and means to cause said pinion to roll along said gears, and thereby effect a relative movement of said platen and said axle, comprising a 35 ratchet-wheel connected with said pinion a

pawl for actuating said ratchet-wheel, and manually-operable means for reciprocating the pawl.

15. In a typewriting machine, in combination, a platen, a shaft on which said platen is mounted, feed-rolls yieldably urged toward said platen, feed-roll cast-off mechanism, including a finger-lever and a link through which said lever effects the cast-off operation, means to effect a shifting of said platen on said shaft, including a ratchet-wheel, revolvably mounted on said shaft, and means to actuate said ratchet-wheel, including a pawl pivoted on said link, means urging said pawl toward effective position with reference to said ratchet-wheel, and means whereby said pawl will be withdrawn from effective position on said link when the latter reaches a predetermined point in its return movement, and will be permitted to return to effective position when the link reaches that point in its actuating movement.

16. In a typewriting machine, in combination, a rotatable platen, feed-rolls to cooperate therewith, means to rotate said platen, feed-roll cast-off mechanism, and means operable by said feed-roll cast-off mechanism to operate said platen-rotating means.

JOHN WALDHEIM.
